UNITED STATES PATENT OFFICE.

MOSES C. NIXON, OF CHICAGO, ILLINOIS.

WINDMILL.

1,246,008.

Specification of Letters Patent.

Patented Nov. 6, 1917.

Application filed July 25, 1917. Serial No. 182,756.

To all whom it may concern:

Be it known that I, MOSES C. NIXON, of the city of Chicago, in the county of Cook and State of Illinois, have invented certain 5 new and useful Improvements in Windmills, of which the following is a specification.

The objects of the invention are to provide for automatic lubrication of certain working parts, a pull-out mechanism and 10 such other improvements as may hereinafter appear; and consists, preferably, in the construction hereinafter described.

In the drawings, Figure 1 is a side elevation of a windmill head, with parts of the 15 incasement and the covering cut away to better show the working parts; Fig. 2 is a plan view with the covering removed and with parts broken away; Fig. 3 is a section of obscure parts of Fig. 1, on a reduced scale, 20 and at right angles to the same; Fig. 4 is an enlarged sectional view of a part of the cams, cut through the spill-way, showing bucket in connection with one of the cams for elevating the oil and part of the run- 25 way that conveys the oil to journal bearings; Fig. 5 is an enlarged sectional view of a part of the gear-wheel, cut through the spill-way, showing bucket in connection therewith for elevating the oil from the reservoir and a 30 part of the run-way that conveys oil to journal bearings; Fig. 6 is the central part of the pull-out lever and a section of the main-frame, showing arrangement whereby open space between the lever and incasement is 35 obviated when the lever is rocked; Fig. 7 is a part of the main-frame and pull-out lever, showing a modified form of the latter, and Fig. 8 is a sectional view showing the chamber or reservoir in the hubs of lever 15, pit- 40 man 14 and the pump-rod head, with a loop of felt therein.

In the drawings, similar numerals of reference indicate corresponding parts in the different views, and referring to the same, 1 45 is the incasement, which in this case is also the main-frame, and 2 is a covering for the same. Journalized in the main-frame is the wheel or driving shaft 3, to which is rigidly secured gear-pinion 4. This pinion meshes 50 with and drives the gear-wheel 5, secured to shaft 6, journalized in the main-frame. Secured to shaft 6 is a double cam or two cams 7 and 8 side by side. Secured to the main-frame is a shaft 9, the front bearing of

which is removed to better show the interior. Pivotally mounted on shaft 9 is a rocking frame 10, which carries two rollers, of which roller 11 contacts with cam 7 and roller 12 with cam 8. As they revolve, one cam forces its mating roller outwardly carrying with it the rocking frame; then as the full movement in that direction is reached the other cam drives its mating roller and the frame in the opposite direction, thus creating a rocking movement of the frame. 65 Pivotally secured to this rocking frame at 13 is a pitman 14, which is pivotally connected with lever 15, as by pivot-pin 16. Said lever is pivoted on shaft 17, and to its free end is pivotally secured the pump-rod 18, as by pivot-pin 19. As the pivot-pin 16 is tapped into lever 15 the length of stroke of the pump-rod may be increased or decreased by shifting said pivot-pin to threaded holes 20 or 21 as the case may require. 75

The cams 7 and 8 are so shaped and proportioned that the movement of the rocking frame will be comparatively slow with increased power while lifting the load and with a comparatively quick return. As the weight of the pump-rod assists the power on the down stroke and acts against it on the upward stroke, it is evident that less power is required to force the plunger downward than to raise it; hence a more 85 rapid speed is possible on the downstroke than on the upstroke. The demand on the power is thus equalized by constructing the cams as already described, enabling it to perform the work with less power or wind. 90

For the purpose of furnishing automatic lubrication for certain parts, the incasement or main-frame 1 is made to form a reservoir 22, for holding a supply of oil, in which a piece of tubing 23 is firmly secured in line 95 of the tubular mast 24, so as to afford free working space for the pump-rod, and extends upwardly to a point above surface 25 of the oil. This tubing 23 may be either a separate piece, an extension of the tubular mast, or may be in a tubular form cast integral with the incasement, but in either case it is essential that it be so constructed as to form a dependable container for a supply of oil. As it is necessary to retain and return the surplus oil from the journal bearings to the reservoir, said bearings are inclosed in extensions 1' and 1'' of the

incasement, and the bolts for securing the bearings are anchored by placing their heads into grooves 27. It being necessary to extend the wheel shaft 3 through the in- 5 casement a closely fitting washer 28 on said shaft is provided to turn back the surplus oil, and to give it free access to the reservoir, channels 29 beneath the bearings and open spaces 30 between them and the in- 10 casement are provided.

Opposite each other and in connection with cam 7 and gear-wheel 5 are similar devices for lubricating the journal bearings, in which are provided buckets 31, 31' with openings or 15 spill-ways 32, 32', so that as the cam and gear wheel revolve these buckets will elevate oil from the reservoir and in passing spill it into run-ways 33, 33' and 34, 34'. Run-ways 33, 33' convey the oil to the bearings of shaft 3, through oil holes 35, 35'; and the run-ways 34, 34' convey it to cups 36, 36' formed on the caps of the bearings, and to the bearings of shaft 6 through oil holes 37, 37'. To automatically lubricate certain pivotal connections, the hubs 14', 15' and 18' of pitman 14, lever 15 and the head of the pump-rod 18, respectively, are chambered thereby forming reservoirs for a supply of lubricating oil, which may be carried to their respective pivot-pins by capillary attraction, as by loops of felt 38 (see Fig. 8), or other substitute therefor.

It will be observed that the pins 16, 17 and 19 do not rotate, and therefore do not assist capillary attraction, either by entrainment due to rotary motion or by suction, and that the location of the reservoirs does not assist lubrication by gravity, but in the construction shown, capillary attraction alone through loops 38 is sufficient to lubricate the pivots.

It being desirable that the incasement in combination with the covering 2, which is secured thereto, be storm-proof and that the pull-out mechanism be operated through the mast, a mechanism has been devised consisting of a bell-crank lever mounted on shaft 17 and having an operating arm 39 extending to a point over the mast, with a rod or wire 40 attached to its end, said wire leading down through the tubing 23 and mast 24, so as to be operative from below. This bell-crank lever has another arm 41 extending downward through slotted opening 42 in the incasement, and its lower end is connected with a lug 43, by means of rod 44. Said lug is a rigid part of vane-hinge 45 which is pivotally connected to brackets, of which the upper bracket 46 extends from extension 1" of the incasement 1, and the lower bracket 47 extends from the lower part of said incasement (see Fig. 3) and is much longer, which allows ample room between the incasement and the vane-hinge pivot to permit the lug 43 to pass between

them. The vane stem 48 is rigidly secured to the vane-hinge, is broken off in the drawings, and the vane, which may be of the usual form, is not shown. Around the vane-hinge pivot-pin 49 is placed torsion spring 50, which has a hook 51 at its upper end adapted to catch upon rib 52 of the vane-hinge. The lower end of this spring is turned downward and adapted to enter hole 53 in tension piece 54. This tension piece is placed upon the vane-hinge pin and is provided with a rim 55, upon which the spring rests and its hub extends upwardly into the spring. At the upper end of this spring a rimmed collar 56 is provided, which extends downward into the spring, the rim 57 being intended to prevent the collar from working too far down. The object of this collar and the upwardly extending hub of the tension piece is to keep the spring centrally located as to the hinge-pin. From the lower part of the incasement extends a bracket 58, to which is attached a rod 59. Said rod passes through a hole in the arm of the tension piece and by the use of nut 60 the tension on the torsion spring may be adjusted to meet requirements. In operation of the pull-out mechanism, the rod 40 is drawn downward, depressing arm 39, forcing arm 41 outwardly, carrying with it 95 rod 44 and connecting parts, thereby causing the vane to pivot and permitting the mill to become inoperative, and when released the torsion spring carries it back into normal position.

In Fig. 7 of the drawings, a modified form of the pull-out lever is shown, in which arm 39' is rigidly secured to shaft 17', said shaft extending through the wall of the incasement, and to its outer end is rigidly secured arm 41', thus producing a modified form of the pull-out mechanism with the storm-proof feature.

To permit arm 41 of the pull-out lever to operate beneath the incasement the latter is cut under as indicated in dotted outline 61 in Fig. 1, and shown in Figs. 2 and 3; and with a view of making the incasement more storm-proof, its wall is brought close to the hub 62 of the pull-out lever. Said hub is provided with a rim 63, which continually fills opening 42 at one end, and the web 64 that connects the two arms of the pull-out lever performs the same function at the other end, thereby preventing an open space occurring when the lever is rocked. Also to make the incasement more storm-proof, the covering 2, which is preferably made of galvanized steel, is formed with an offset 2' so as to rest upon the incasement and extends downwardly over the same, and is secured thereto.

While I have shown and described the preferred construction of my invention I do not wish to be limited to the details

shown as changes may readily be made without departing from the spirit of my invention.

What I claim is:

- 5 1. In a windmill, the combination with a supporting frame constructed to embody a reservoir for lubricant, of power transmitting mechanism mounted upon said frame and comprising a part whose movement has a vertical component, a dipper carried by said part in position to elevate lubricant from the reservoir, and ways for receiving said lubricant and conveying it to parts to be lubricated.
- 15 2. In a windmill, the combination with the supporting frame constructed to embody a reservoir for lubricant, of power transmitting mechanism mounted upon said frame and comprising a part whose movement has a vertical component, a dipper carried by said part in position to elevate lubricant from the reservoir, and ways for receiving said lubricant and conveying it to parts to be lubricated, and means for returning the surplus to the reservoir.
- 25 3. In a windmill, the combination with the supporting frame constructed to embody a reservoir for lubricant, of power transmitting mechanism mounted upon said frame and comprising a gear wheel, a dipper carried by said gear wheel in position to elevate lubricant from the reservoir, and means for receiving the lubricant and conveying it to parts to be lubricated.
- 35 4. In a windmill, the combination with the supporting frame constructed to embody a reservoir for lubricant, of power transmitting mechanism mounted upon said frame and comprising a cam, a dipper carried by said cam in a position to elevate lubricant from the reservoir, and means for receiving the lubricant and conveying it to parts to be lubricated.
- 45 5. In a windmill, the combination with the supporting frame constructed to embody a reservoir for lubricant, of power transmitting mechanism mounted upon said frame and comprising a gear wheel and cam, dippers carried by said gear wheel and cam in position to elevate lubricant from the reservoir, and means for receiving the lubricant and conveying it to parts to be lubricated.
- 55 6. In a windmill, the combination with a supporting frame constructed to embody a reservoir for lubricant, of power transmitting mechanism comprising a revoluble shaft, a dipper carried by said shaft in position to elevate lubricant from the reservoir, and ways for receiving said lubricant and conveying it to parts to be lubricated.
- 65 7. In a windmill, the combination with a supporting frame, of a reservoir for lubricant, the power transmitting mechanism of the windmill mounted on said frame and comprising a part whose movement has a vertical component, a dipper carried by said part in position to elevate lubricant from the reservoir, ways for receiving said lubricant and conveying it to parts to be lubricated, and means for returning the surplus to the reservoir.
8. In a windmill, the combination with the supporting frame constructed to embody a reservoir for lubricant, said reservoir having a tubular form therein and extending upward to a point above the lubricant and in line with the mast, power transmitting mechanism one of the members of which embodies means to elevate lubricant, means to receive and convey the lubricant from the elevator to the bearings, and means for returning the surplus lubricant to the reservoir.
9. In a windmill, the combination with a supporting frame, of a lever fulcrumed thereon intermediate its ends, cams constructed and arranged to alternately actuate said lever by engaging its ends, a lever connected to an actuated member, a pitman connecting said levers, and means for driving said cams.
10. In a windmill, power transmitting mechanism comprising an actuating member, a pitman containing an oil reservoir, a pivot pin connecting said pitman and actuating member, and means for conveying oil by capillary attraction from the reservoir to said pivot pin.
11. In a windmill, power transmitting mechanism comprising a lever, a pin carried by said lever, an actuated member mounted on said pin and having an oil reservoir therein, and means whereby oil may be conveyed by capillary attraction from the reservoir to said pin for lubricating the same.
12. In a windmill, power transmitting mechanism comprising a stationary pivot, a lever mounted on said pivot and having a hub with an oil reservoir therein, means whereby oil may be conveyed by capillary attraction from the reservoir to said pin for lubricating the same.
13. In a windmill, the combination with power transmitting mechanism, of an actuated member, pivotal connection between the power transmitting mechanism and actuated member, the hub of said connection being formed to serve as a bearing and with a lubricant reservoir adjacent to said bearing and the pivot being non-rotary, and means for conveying lubricant by capillary attraction from the reservoir to said pivotal connection.
14. In a windmill, power transmitting mechanism comprising pivoted connections each of which connections comprises a hub surrounding a non-rotary pivot, an oil reservoir in said hub, and means for conveying oil by capillary attraction from said reservoir to said pivot.
15. In a windmill, the combination with a

supporting frame constructed to embody an incasement adapted to contain lubricant, power transmitting and lubricant feeding mechanism housed in said incasement, a 5 tubular mast upon which said frame is mounted to swing about a vertical axis, a swinging vane mounted upon the outside of said frame, a lever arm within the incasement, operative connections between said 10 arm and said vane, and means connected with said lever and operated through the mast whereby the lever and connections may be operated.

16. In a windmill, the combination with a 15 supporting frame constructed to embody an incasement adapted to contain lubricant, power transmitting and lubricant feeding

mechanism housed in said incasement, a tubular mast upon which said frame is mounted to swing about a vertical axis, a 20 vane mounted upon the outside of said frame, a bell-crank mounted upon said frame and having one arm extending within said incasement to a point over the mast, and the other arm extending outside of said 25 incasement and operatively connected with the vane, and means connected with the bell-crank lever and adapted to operate through the mast.
